UNITED STATES PATENT OFFICE.

FRANK L. O. WADSWORTH, OF PITTSBURGH, PENNSYLVANIA. ASSIGNOR TO HUGHES TOOL COMPANY, OF HOUSTON, TEXAS, A CORPORATION OF TEXAS.

ROTARY BORING-DRILL.

1,388,496.

Specification of Letters Patent. Patented Aug. 23, 1921.

Application filed January 29, 1919. Serial No. 273,715.

To all whom it may concern:

Be it known that I, FRANK L. O. WADSWORTH, a citizen of the United States, residing at Pittsburgh, Pennsylvania, have invented a certain new and useful Improvement in Rotary Boring-Drills, of which the following is a full, clear, and exact description, such as will enable others skilled in the art to which it appertains to make and use 10 the same.

My invention relates to rotary boring drills for use in drilling oil or water wells and the like. It has application to rotary bits that are provided with revoluble cutters of either the cone roller or the disk type; or to other similar rotary drills, designed to drill in softer formation such as 15 gumbo, shale or sand.

One object of my invention is to provide 20 a drill in which the rotary cutters will have a positive drive in addition to the rolling movement that is imparted to the said cutters by the rotation of the drill stem and thereby prevent the "balling up" and locking 25 of the said cutters in the material at the bottom of the bore hole.

Another object is to provide a drill, for 30 the purpose described, which may be operated in such a manner as to secure a more effective shearing and excavating action on certain kinds of material, and also prevent a too rapid penetration of soft or loose strata.

A further object is to provide means for 35 forcing the flushing water into the end of the bore hole in jets, whose velocity is independent of any difference in pressure between the down flowing and upflowing currents of liquid in the hole.

Another object is to combine, in one drill 40 structure, the more important features of advantage of both reciprocating and rotary types of drills.

Various other objects and advantages will 45 appear in the description which follows; novel features of improvement which characterize my invention will be pointed out with more particularity in the claims appended hereto.

In the drawings Figure 1 is a side view 50 partly in section on the line 1—1 of Fig. 3; Fig. 2 is a side elevation taken at right angles to the position shown in Fig. 1; Fig. 3 is a top plan view, on an enlarged scale, of the

same; Fig. 4 is a transverse section (on the 55 scale of Fig. 3) on the line 4—4 of Fig. 1; Fig. 5 is a perspective view (also on an enlarged scale) of the ratchet ring used with one form of my invention; Fig. 6 is a side elevation (on the scale of Figs. 1 and 2) of 60 the central gear casing of the drill head; Fig. 7 is a horizontal cross section viewed from below in the line 7—7 of Fig. 1, showing a modified construction and arrangement of 65 the drill cutters and gear housing; Fig. 7^A is a transverse section on the line 7^A—7^A of Fig. 1; Fig. 8 is a longitudinal section 70 through the drill axis, illustrating the embodiment of my invention in a single central cutter type of boring tool; Fig. 8^A is a broken section on the line 8^A—8^A of Fig. 10; Fig. 9 is a side elevation of the lower portion 75 of the construction illustrated in Fig. 8 (the part of the head of the left of the line 9—9 of Fig. 8 being removed) Fig. 10 is a transverse section of this same construction 80 on the line 10—10 of Fig. 8; Fig. 11 is a side elevation partly in section of another embodiment of my invention in which the boring tool is of the horizontal disk cutter 85 type; Fig. 12 is a transverse sectional view (on a reduced scale) on the line 12—12 of Fig. 11; Fig. 13 is a longitudinal section 90 illustrating the application of my invention to another form of vertical, or inclined cutter disk drills; Fig. 13^A is a broken section on the line 13^A of Fig. 13; Fig. 14 is a transverse section on the line 14—14 of Fig. 13; Fig. 15 is a side elevation of this last construction; and Fig. 16 is a detail cross sectional view of a part of this drill structure.

Referring with more particularity to the illustrations of Figs. 1 to 6 of the drawing—wherein like parts are designated by like numerals throughout the several views—I 95 have here shown a bit of the rotary disk type, which comprises a slotted drill head 6 with an upper threaded shank 7, reduced in diameter for attachment to a coöperating driving head 8; and two vertical or upright 100 disk-shaped cutters 10 which are mounted in the slotted head on a pin or shaft 11 that is arranged at substantially right angles to the axis of rotation of the drill. Each of the disks 10 is of the "4 point" or double 105 edged cutter type, and is provided with the usual bushings 12 and washers 13, and a bevel gear member 14, is secured to the inner

face of each of the said cutters by means of screws 15, or other similar suitable instrumentalities.

These gears 14 mesh with a bevel gear or pinion 16 which is mounted on the lower squared end of an upright shaft 17, that extends upwardly through the drill head 6 and nearly to the top of driving head 8, as shown in Fig. 1. This shaft is provided 10 with a flange or collar 18 which fits within an annular seat formed in the drill head and serves to hold the said shaft against longitudinal movement with respect to the said head. In order that these parts may be 15 properly assembled, the drill head 6 is split longitudinally along its central plane, parallel with the cutters 10, and the said parts are held in assembled position by the cutter shaft 11 and by the driving head 8. The 20 gears 14 and 16 are completely inclosed in a casing or housing 50, which is fitted into a rectangular recess in the lower end of the drill head—between the slots in which the cutters 10—10 are housed—and which is provided 25 with circular flanges that fit into annular recesses on the inner faces of the cutters 10. This housing is also provided with an opening at the upper side to receive the shaft 17 and with a central cross rib 49 30 which is bored to receive the cutter shaft 11.

In assembling the parts just described the pinion 16 is first placed in the housing 50 and the shaft 17 is then passed through the opening in the upper side of the housing and 35 its lower squared end engaged with the pinion. A washer 51 is then slipped between the lower face of the pinion and the adjacent upper face of the cross rib 49; and the gears 14, 14, are next placed in position against the 40 two sides of the housing. The two sides of the divided head 6 are then brought together against the opposite outer faces of the cutter disks, and secured in place by first inserting the cross shaft 11, and then screwing the upper 45 threaded portion 7 into the lower end of the driving head 8. The casing 50 may also be provided with dowel pins 52—52 which are adapted to engage in holes in the two halves of the head, and thus assist in the assembling and clamping of the parts in place. The driving head 8, comprises an outer sleeve member 19, into which the drill head is secured, and an inner member 20 that is adapted to reciprocate within the said sleeve 50 member. The upper end of the inner member 20 is reduced in diameter and threaded at 21 for attachment to a drill stem, not shown. The upper end of the sleeve member, 19, is bored to a larger diameter than the lower part, thus forming two piston chambers that are separated by an annular shoulder 22; and the reciprocable member 20 is correspondingly shaped to form a two part piston whose upper and lower ends fit 60 closely within these two piston chambers.

Longitudinal slots 23, 23 are formed in the outer surface of the reciprocating piston member to receive inwardly projecting pins 24, 24 that are fixed in the part 19, and slide in the slots 23.

70

The inner portion of the piston member 20 is recessed to receive the upper portion of the shaft 17. This recess,—as indicated at 25—is of larger internal diameter than the shaft 17 and extends upwardly nearly to the top 75 of the member 20, where it terminates in a small passage 26 that communicates with the upper end of the threaded shank 21 for the introduction of lubricant. The passage 26 is closed by a threaded plug 27.

80

The shaft 17 is provided on its upper peripheral surface with two spiral grooves 35 and 36. At the lower end of this grooved surface the recess 25 is enlarged in diameter to form a small clutch chamber 28, the upper and lower ends of which are threaded interiorly to receive upper and lower ratchet faced clutch members 29 and 30 respectively. The jaws of these clutch members face each other and are separated to provide space for 90 two reciprocable coöperating clutch rings 31 and 32. These clutch rings contact rotatably with a loose washer interposed between the inner adjacent faces of the rings, and the outer faces thereof are toothed to 95 coöperate with the clutch members 29 and 30 respectively. Each of the clutch rings 31 and 32 is provided with an inwardly projecting spline or key—which may conveniently be formed by flattening the inner enlarged ends of pins 33 and 34—which fit 100 slidably within the grooves 35 and 36, respectively. Each clutch ring and its coöperating clutch member are also recessed interiorly on the toothed sides to provide 105 seats for helical springs 37 and 38 which serve to normally hold the clutch rings 31 and 32 out of engagement with the members 29 and 30.

100

A heavier helical spring 39 surrounds the 110 shaft 17 and is interposed between the upper threaded end 7 of the drill head and the lower end of the clutch member 30. This spring tends to hold the cutters 10 in working contact with the bottom of the hole, 115 when the reciprocating member 20 is drawn upwardly in operation. It also serves to cushion the shock of the down stroke, and to gradually vary the pressure applied to the revolving cutters by the reciprocating movement of the drill stem thereby preventing 120 any violent jarring of the operating parts when the drill is in operation.

120

Flushing water is supplied to the slots 9 in which the cutting disks are mounted by 125 a novel arrangement. A plurality of channels 40—of which I have shown four in Figs. 1 and 3,—lead from the upper end of the reciprocating member 20 to the lower end of the larger piston portion of that 130

member, and open into the annular space 41 between the shoulder 22 and the adjacent end of the said piston element. From this space, one or more ducts 42 lead to another 5 annular groove 43 between the lower end of the sleeve 19 and the head 6. From the space 43 two or more channels 44, 44 lead to the openings in which the cutting disks 10 are housed. The upper end of each channel 10 is enlarged to receive a valve seat 45 and the channel is closed against upward passage of water by a spring pressed ball valve 46 in the said valve seat.

In the construction just described the drill 15 stem, to the lower end of which my improved drill is attached, will be both rotated and reciprocated. This combined rotary-reciprocating movement may be imparted to the stem by any well known device, and as such 20 device is not a part of my present invention, it is not here shown. The rotative movement of the drill stem will be imparted directly to the inner reciprocating member 20 and will be transmitted therefrom to the 25 outer sleeve 19 by means of the pins 24, 24 fitting within the slots 23, 23; and the head 6 will thus be rotated, causing the cutters 10 to roll on the bottom of the hole and to cut away and disintegrate the material at that 30 point, in much the same way as in the operation of the ordinary types of rotary disk drills.

The reciprocation of the drill stem will 35 also be directly communicated to the member 20 which will slide up and down within the sleeve member 19—the slots 23, being of sufficient length to permit the desired range of reciprocating movement. Fig. 1 shows my drill with the parts in the lowest point 40 of the stroke in the reciprocation of the drill stem. On the downward stroke the upper spring 38 will be compressed and the clutch member 29 will engage the jaws of the clutch ring 31 to prevent rotation thereof. 45 The clutch ring 32 will, however, be free to rotate, being held out of engagement with the jaws of the clutch 30 by the spring 37. Under these conditions, the engagement of the spline or key of the ring 31 with the 50 groove 35 will revolve the shaft 17 in the direction of rotation of the drill stem, (a clockwise rotation as viewed from above) and this movement will be transmitted, through the gears 14 and 16 to the cutter 55 disks 10, 10 and revolve the said disks positively in the same direction in which they tend to roll on the bottom of the hole as the drill stem and drill head rotate. On the upward stroke of the drill stem, the clutch ring 60 31 will be disengaged from the clutch member 29 and the clutch 30 will engage the ring 32, holding the latter against rotation. The upward motion of the member 20 will now cause the spline or key of the clutch 65 ring 32 to revolve the shaft 17; and as the spiral groove 36 (in which the key 34 is engaged) is cut in a reverse direction to that of the groove 35, this upward movement will cause the shaft 17—and the cutters 10, 10 that are geared thereto—to revolve in the 70 same direction as before.

It is clear of course that only one clutch ring might be employed and that this ring could engage with either of the grooves, 35 or 36 to give the shaft 17 an intermittent 75 rotary movement on either the upward or the downward stroke of the drill stem. It is also clear that the positive rotary movement of the shaft 17—whether it be continuous or intermittent—may be varied, both 80 as to direction and as to speed, by varying the pitch of the spiral driving grooves.

It is further obvious that the pins 24, 24—which engage in the slots 23, 23 and serve to positively rotate the drill head in synchronism with the drill stem—might be removed; and a rotary movement indirectly imparted to the drill head by a simple reciprocating movement of the drill stem. In this case the upward and downward movements of the member 20 will impart a positive movement of rotation to the shaft 17, and this will, in turn, positively revolve the cutter disks 10, 10 which will roll on the bottom of the hole and carry the rotary drill head around with them. The action is then the reverse of that of an ordinary rotary disk drill—(in which the rotation of the drill head serves to revolve the cutters by the rolling contact of the latter with the material)—the rotation of the drill head being produced in this last described arrangement, by the rolling of the positively driven toothed cutters 10, 10 on the surface upon which they rest.

The reciprocation of the drill stem and the member 20 performs the further important function of forcing the flushing water into the bottom of the bore hole, and against the cutters, in a succession of high velocity 100 jets. On the upward stroke of the piston member 20 the valves 46 will open to allow free passage of the water, from the hollow drill stem to the annular piston chamber 41, and thence on, through the open passage ways, 42, 43 and 44, to the openings in which the cutter disks are housed. The member 20 maintains a tight sliding fit with the outer sleeve 19 by means of packing rings 48 and the frictional engagement between these parts tends of course to lift the drill head on each upward movement of the driving head; but this lifting tendency is counteracted in part by the pressure of the water on the shoulder 22 and in part 115 by the tension of the spring 39; and these jointly acting forces—supplemented by the weight of the drill head parts—serve to hold the cutter members in constant operative engagement with the material at the bottom 120 125 130

- of the bore hole. On the downward stroke, the valves 46 close and the upper piston element of the member 20 forces the water out of the annular piston chamber 41 and expels it from the openings 44 in a series of violent jets or spouts, that will be very effective in washing away any disintegrated matter that tends to accumulate around the revolving cutters.
- 10 The lubrication of this bit is accomplished by filling the annular chamber surrounding the shaft 17 with oil, which is introduced into this chamber through the passage way 26. At the lower end of this chamber the 15 shaft 17 is provided with a radial duct, that connects the said chamber with a central duct leading downwardly through said shaft to the interior of the housing 50, which is also filled with heavy oil or grease.
- 20 By this means all of the operating parts are constantly and copiously supplied with lubricant, and are thus fully protected against the action of the water and mud surrounding the drill head.
- 25 In the construction shown in Figs. 1 to 6 the cutter disks 10, 10 are mounted coaxially, and are, as already stated, of the two edged or "four point" type more fully described in my application Ser. No. 200,672 filed November 26, 1919, later abandoned and thereafter, on March 26, 1919, application No. 300,004, refiled therefor. My present invention is not however, limited to rotary drills of this type, but is applicable 30 to many other forms of rotary disk or roller bit constructions. In Fig. 7, for example, I have illustrated a drill head provided with two vertical disk cutters 10^a 10^a which are laterally offset with respect to each other 35 so as to bring only the forward advancing edges, and the adjacent peripheral surfaces, of the cutters into engagement with the material at the end of the bore hole. In this construction the cutters are mounted on a 40 shaft 11^a, which is provided with two eccentrically turned portions 55 and 56, and with a central squared portion 57, the upper side of which forms a support for the washer 51 that is interposed between it and the lower 45 face of the pinion 16^a. Each cutter 10^a is provided with a bevel gear 14^a, the teeth of which are shaped to engage with the teeth of the bevel pinion 16^a; and the gears and pinions are inclosed in a casing or housing 50^a the upper edge of which is fitted into a 55 rectangular recess in the lower end of the divided head 6^a—the whole arrangement being similar to that illustrated in Figs. 1 to 6; save that the casing 50^a is not in this case provided with any central cross web corresponding to the part 49 of Figs. 1-6 construction. The construction of Fig. 7 also differs in detail from the structure first described in having elastic expansion rings 58, 60 (or 59) inserted between the faces of the 65 circular rings on the ends of the casing member 50^a and the adjacent faces of the cutter disks 10^a 10^a;—these packing rings being particularly useful in preventing any leakage of liquid into or out of the interior 70 of the casing when the cutter members are forced outwardly by the unbalanced pressure of the cut on the forward advancing edges of the disks. The cutters themselves also differ from those shown in Figs. 1, 2, 3, 75 4 and 6 in having peripheral surfaces that are provided with a series of circumferentially or spirally disposed grooves, so shaped as to form a succession of secondary cutting edges separated by intermediate crushing 80 and disintegrating surfaces. But it is obvious that any suitable form of cutting crushing disk members—with either toothed or grooved, or plain peripheral surfaces—may be used in either of the rotary disk constructions above described.
- 85 The main difference between the structure of the two drill heads shown in Figs. 1 to 6 and Fig. 7 results from the positioning of the cutter disks relative to the axis of the 90 head. When these disks are centrally and co-axially mounted—as in the first construction described—the gears 14 and the pinion 16 are ordinary bevel gears having conical pitch surfaces. When the two disks are 95 axially offset with respect to each other—as in Fig. 7—the gears 14 and 16 must be formed with hyperbolical pitch surfaces and provided with teeth cut at a slight angle to the axes of the gears. But the offsetting of 100 the gear axes with respect to each other is so small that the design and the cutting of these spiral tooth gears offers no particular difficulty; and the teeth are so thoroughly protected against wear (by being inclosed in a 105 casing filled with lubricant) that either form of gear will operate for a long time without replacement. The disk members 10 or 10^a, and the bushings therefor (12 and 13 or 12^a and 13^a) may, of course, be easily and 110 quickly replaced whenever necessary.
- 115 The drill head shown in Fig. 7 is designed for attachment to the same form of driving head as is illustrated in Figs. 1 to 6; and the operation of the combined structure thus produced is in all respects similar to that already described.
- 120 In Figs. 8, 9 and 10 I have illustrated the application of my invention to a rotary drill of the single central disk type of construction. In the specific form here shown the single cutter 10^b is mounted to revolve in a plane that is slightly inclined to the axis of the drill head, and is provided with two opposite cutting edges of slightly different diameter that are adapted to shear away the 125 material at the sides and bottom of the bore hole on both the forward advancing face and the rearward following face of the rotating disk. The inner face of this disk is 130

recessed and a bevel gear 14^b is screwed thereto by means of screws 15^b or in any other suitable manner. The connected gear and disk are revolvably mounted on the inclined stud shaft 11^b which is provided with a squared section 57^b and is rigidly secured in the downwardly extending leg of the head 6^b; and the revolvable member is held in place on the shaft 11^b by means of a plate 10 61 which is secured in place against the beveled side of the head and the shouldered end of the shaft by means of screws 62 and the split cone nut 63, the latter being locked in place by means of a lead or Babbitt metal 15 seal 64, which fills the space between the capped end of the nut 63 and the slotted or notched end of the shaft 11^b.

The head 6^b is provided with two longitudinally disposed circular openings, 42^b and 20 65 which are eccentrically arranged with respect to the axis of the drill head and extend upwardly to the upper or rear end thereof. A shaft 17^b is centrally mounted in the larger of those openings, and extends 25 downwardly through a bearing in the lower end of the head. The lower end of this shaft is squared or flattened on one side to enter a correspondingly shaped socket in the bevel pinion 16^b, which is arranged to engage with the gear 14^b; and the said shaft is held against longitudinal movement by a shoulder or collar portion 18^b which engages with a seat at the bottom of the opening 65 and is held therein by a plate 66. The upper end of the shaft 17^b is provided with two 30 or more left hand spiral grooves 36^b which are engaged by a left hand nut 32^b; and this nut is provided on its lower face with teeth which are adapted to engage with the correspondingly toothed upper face of a clutch ring 30^b—the construction and arrangement of these last described elements being similar to that of the correspondingly numbered parts in the first described structure save 35 that the pitch of the grooves and the inclination of the clutch teeth are oppositely disposed in the two cases. The nut 32^b is slidably mounted in the enlarged end of a hollow shaft 67, which extends upwardly 40 through a packing box 68 that closes the upper end of the opening 65, and is secured to the cap of a reciprocable driving head or sleeve 8^b that is bored to fit closely over the exterior periphery of the drill head 6^b, and 45 is threaded at its upper end to engage with the hollow drill stem. The annular space between the sleeve members 8^b and 67 and the top of the drill head 6^b constitutes a piston chamber 41^b, which communicates with 50 the interior of the hollow drill stem through a valve seat and spring pressed ball valve 45^b and 46^b; and also communicates with the passage way 42^b through a similar valve seat and ball valve 69 and 70.

65 The gears 14^b and 16^b in the lower part

of the drill head are surrounded and inclosed by a box shaped casing 50^b, which fits into an L shaped recess in the bottom of the drill head 6^b and is screwed therein by means of screws 71. This casing is provided on its 70 outer face with a circular flange or rib that fits closely within the annular recess on the adjacent inner face of the disk member 6^b, and is further provided with an opening in its upper wall for the passage of the shaft 17^b.

In assembling the parts of this construction, the gear pinion 16^b is first placed in the casing 50^b and the latter is then slid into position, over the squared portion 57^b of the shaft 11^b, and screwed in the recess in the 80 drill head by the screws 71. The shaft 17^b is then inserted through the registered openings in the top of the casing and the lower end of the drill head, and secured against longitudinal movement by the insertion of 85 the plate 66. The hollow shaft 67—carrying the nut 32^b and the clutch ring 30^b is next put in place over the end of the shaft 17^b and the packing box 68 screwed into position. The driving head 8^b is next engaged 90 with the drill head and the sleeve member 67 screwed to the driving head by means of the threaded cap 72. The cutter disk 10^b carrying the gear 14^b—can then be put in place and secured in position by the cap 95 plate 61. Before this disk member is put in position the interior of the box 50^b should preferably be filled with a thick heavy grease or oil; and after all the parts are assembled as above described the hollow shaft 100 67 and the annular space between the coöperating shaft 17^b and the wall of the opening 65 are also filled with a somewhat more fluid lubricant that is poured in through the opening in the cap 72,—this opening being 105 then closed by the plug 27^b.

The lower end of the passageway 42^b opens on the beveled face of the drill head, and there communicates with lateral passages, that are formed by cutting grooves in the engaging faces of the head and the attached plate 61. These lateral passages terminate in discharge orifices 73, which are inclined downwardly and forwardly in the direction of rotation of the rotatable disk 10^b; and the peripheral face of the latter is preferably provided with ratchet shaped teeth 74 whose rear edges are arranged at nearly right angles to the circumference of the disk. These teeth 74 may be arranged transversely of the peripheral face of the cutter—as shown in Figs. 1, 2, 3 and 4—or spirally disposed therein; but they are preferably of “herringbone” form as illustrated in Fig. 9; this being the form that is particularly effective in 115 producing a rotation of the disk by the pressure of the cut on both the advancing and following edges of the cutter faces.

The operation of this drill construction is similar to that already described. The 120 125 130

drill stem to which the driving head 8^b is directly attached is preferably given a joint reciprocating and rotary movement. The rotary movement is communicated directly 5 to the drill head 6^c by means of keys or pins secured to the driving head 8^b and engaging in grooves 23^b 23^b (see Fig. 10) that are cut in the periphery of the drill head. The reciprocating movement of the driving head is communicated 10 to the member 67 and on the upward stroke of this member the nut 32^b is engaged with the clutch ring 30^b, and thereupon serves to positively rotate the shaft 17^b in a counterclockwise direction—as viewed 15 from above—at a speed which is dependent upon the pitch of the grooves 36^b and the linear velocity of the reciprocating movement. The positive rotation of the shaft 17^b is communicated—through the gears 16^b 20 and 14^b—to the disk cutter 10^b and causes the latter to revolve in the same direction as it tends to roll on the bottom of the bore hole when the drill head rotates. On the downward stroke of the driving head the 25 frictional engagement of the nut 32^b with the grooved portion of the shaft 17^b serves to disengage the nut from the clutch ring 30^b and thus leaves the shaft 17^b free to rotate independently of the movement of the driving heads. But it is of course obvious that the shaft 17^b might be provided with two sets of oppositely disposed spiral grooves; and the reciprocating member 67 arranged 30 to carry two sets of nuts and clutch rings—35 arranged as shown in Fig. 1,—so that the shaft 17^b could be driven positively in the same direction on both the upstroke and the down-stroke of the driving head.

During the upward movement of the 40 member 8^b the cylinder or piston chamber 41^b is filled with water from the interior of the hollow drill stem—by the free opening of the valve 45^b—and the hydraulic pressure of this water on the end of the 45 drill head 6^b serves to assist the weight of the head in keeping the cutter member 10^b in operative engagement with the bottom of the bore hole. If these forces are not alone sufficient to maintain the desired pressure 50 on the cutter disk their effect may be supplemented and augmented by the compressive tension of a spiral spring 39^b that can be interposed between the lower end of the reciprocating sleeve 67 and the plate 66 at the bottom of the opening 65.

On the downward movement of the driving head the valve 45^b closes and the water then filling the piston chamber 41^b is then forced out through the passage way 42^b and 60 expelled at high velocity, from the orifices 73, against the teeth of the cutter 10^b. This action not only tends to wash away all detritus from the sides and face of the cutting disk—thereby keeping the teeth of the cutter in clean and effective cutting condi-

tion,—but also serves to produce a semi positive driving action that will revolve the disk in the same direction as it is driven by the operation of the reciprocating-rotary-conversion-gear members 14^b 36^b. This construction therefore embodies two separate but coöperating means for utilizing the reciprocating movement of the drill stem and driving head to effect a rotary driving movement of the revoluble cutter disk; and either 70 one or both of these conversion gear instrumentalities may be arranged to operate either intermittently (or in one direction only of the reciprocating movement) or continuously in both directions of reciprocation. 80

In Figs. 11 and 12 I have illustrated another embodiment of the main features of my present invention in a rotary bit construction of the horizontal disk type—which forms the subject matter of another of my 85 copending applications Ser. No. 215589—in which the two cutter members 10^c 10^c revolve on axes that are nearly parallel with the axes of rotation of the drill head 6^c. In the particular embodiment illustrated in Figs. 90 11 and 12 the cutter disks are rigidly secured on (or made integral with) the shaft supports 11^c and the latter are revolvably mounted in bushings 12^c, that are removably secured—by screws 76 or other suitable 95 means—in the diametrically opposed bosses 75, 75 of the drill head 6^c. The upper ends of the shaft supports 11^c are reduced in diameter to receive clutch collars 30^c which are keyed or otherwise secured to the said 100 shafts, and are provided in their upper ends or faces with an annular series of teeth similar to those with which the correspondingly numbered clutch ring of Fig. 1 is provided. Driving gears 32^c, 32^c are rotatably mounted 105 on the peripheries of the clutch rings 30^c, and are provided with teeth 77 that are adapted to engage with the toothed end faces of the clutch rings. The external peripheries of these driving gears are provided 110 with spiral or helical teeth which engage with correspondingly described helical grooves in the opposite faces of a reciprocating rack bar, 67^c that extends upwardly through a packing box 68^c in the top of the 115 drill head, and is secured at its upper end (by the nut 72^c) to the cap of the driving head 8^c. This driving head is bored out to make close sliding engagement with the upper end of the drill head 6^c, and is provided 120 with one or more removable blocks or keys that engage with a corresponding number of longitudinal grooves 23^c, and serve to communicate the rotary movement of the driving head to the drill head. The upper 125 end of the driving head is threaded for attachment to the ordinary hollow drill stem, ordinarily used in driving these rotary drills; and the top of this head is perforated with a number of valve openings 45^c that are 130

closed at their lower ends by a flexible valve plate 46^c. The sides of the hollow drill head 6^c are provided with two or more passages 42^c which lead from the upper end of the head to points adjacent the faces of the cutter disks 10^c 10^c, and are there inclined in such direction as to direct the water flowing through the said passages against the toothed peripheries of the revolute cutters—as 10 shown by the dotted lines in Fig. 12.

In assembling the parts of this horizontal disk bit structure the driving gears 32^c are first put in place through openings in the side of the hollow drill head, and the disk 15 shaft 11^c, bushing 12^c, and clutch collar 30^c (previously assembled as a single unit) are then slid into position from below, and held in position by the bushing screws 76. The rack bar 67^c is then inserted from above 20 and the packing box 68^c screwed in place. The driving head 8^c is next slipped over the upper end of the drill head, and the keys which slide in the grooves 23^c are secured in place on the head. The openings through 25 which the driving gears 32^c are inserted are then closed by caps 79, that are clamped tightly against the outer faces and upper side edges of the bosses 75 by means of screws 80. The interior of the hollow drill head 30 6^c is now filled with heavy oil or other suitable lubricant, through the passageway, 81, and the bar 67^c is clamped in position on the driving head by the cap nut 72^c which also serves to close the end of the oil passage 81. 35 In the operation of this horizontal disk drill the upward movement of the driving head and rack bar 67^c lifts the driving gears 32^c out of clutch engagement with the rings 30^c thus leaving the disk cutters 10^c free to 40 revolve counterclockwise—as viewed from above (see Fig. 12) as the drill head revolves from left to right or in a clockwise direction. During this upward movement the valve plate 46^c flexes downward, opening the passage ways 45^c, and allowing the water in the hollow drill stem to flood the piston chamber 41^c and exert its full pressure on the top of the drill head 6^c. This pressure supplements the weight of the heavy drill head and serves 45 to prevent the latter from moving upward with the driving head. On the downward movement of the driving head the driving gears 32^c are first pushed down until the clutch teeth thereon engage with the clutch 50 rings 30^c; and are then revolved from right to left,—as viewed from above—by the sliding engagement of the helical teeth on the faces of the gears and the rack bar 67^c. This movement serves to positively revolve the 55 cutter disks 10^c in the same direction in which they are moved by the pressure of the cutting engagement with the material at the end of the bore hole, when the drill head is rotated. The descent of the driving head also closes 60 the valve plate 46^c and forces the water in

the piston chamber 41^c downward through the passages 42^c; and expels this water from the lower inclined orifices of these passages in jets which impinge, at a high velocity, on the revolving peripheral surfaces of the 70 cutter disks; thereby not only freeing these surfaces from all accumulations of mud or other detritus, but also serving to assist the action of the rack-gear conversion devices in securing a positive rotation of the cutter 75 members, independently of any rotation of the drill head as a whole.

It is, of course, obvious that the clutch collars 30^c and the coöperating gears 32^c may be arranged to engage only on the up 80 stroke of the driving head—so as to revolve the cutter disks during this movement (as in the Figs. 8-10 construction) and it is further clear that both the direction and the speed of rotation may be changed as desired 85 by reversing or varying the pitch of the helical gear and rack teeth.

In the construction shown in Figs. 13 to 16 the cutter members 10^a 10^d are inclined to the longitudinal axis of the head; and are also offset backwardly with relation thereto, so as to bring only the rear following edges on the outer faces of the disks in cutting engagement with the sides and end of the bore hole. The drill head, 6^a, on which 95 these cutter disks are mounted, is split or divided longitudinally on the planes *e*—*f*, *g*—*h*, which contain the axes of these disks; and the latter are revolvably supported in split bushings 12^a, that are clamped in position between the engaging faces of the divided head by the bolt 62^a and screw collar 84^a that engages the upper threaded end of the said head. The upper end of this head is also bored and grooved to receive the 105 shouldered lower end of a piston extension, 82, that terminates in an enlarged head 83. A hollow sleeve 84 is fitted to the exterior periphery of the head 83, and is closed at the bottom by a split collar 85 which is threaded 110 into the said sleeve and is bored out to fit closely around the piston extension 82. This split collar is also provided with one or more keys or splines which engage with longitudinal grooves 23^a (indicated by dotted lines) 115 on the periphery of the said extension members. The upper end of the sleeve 84 is closed by the driving head cap 20^a which is threaded to engage with the collar of the usual hollow drill stem. This cap member 20^a is 120 perforated with two passage ways, 40^a and 86, both of which are closed at the top by downwardly opening ball valves 46^a. The passage way 40^a leads to the upper end of the piston chamber 41^a above the head 83; 125 and the passage way 86 leads to a covered groove, on the exterior of the sleeve 84 (see Fig. 16) that communicates with the annular chamber 88 below the head 83. This head is likewise provided with two openings 130

communicating respectively with the piston chambers 41^a and 88—these openings being perfectly controlled by the spring pressed ball valves 70^a, and being connected to a common passage 42^a that leads downwardly to the chamber 43^a, between the end of the divided drill head and the piston extension 82. Two other inclined passage ways 44^a lead downwardly through the sides of the divided head 6^a and terminate in orifices that are opposite the inner faces of the inclined cutters 10^a. These faces are provided with radial teeth 90 so formed as to constitute a set of turbine blades for receiving the impulse of the jets of water discharged from the passage ways 44^a, and utilizing said jets to impart a semi-positive revolution to the cutter disks.

A lubrication tube 91 is screwed into a threaded opening at the top of the divided drill head 6^a, and extends upwardly through the passage 42^a and through a stuffing box 68^a that closes the top of that passage. This tube opens at the bottom into an annular recess surrounding the inner flanged ends of the split bushing members 12^a, and constituting—(in conjunction with the tube 91)—an oil chamber for supplying lubricant to the bearing surfaces of the cutter shafts 11^a.

The exterior periphery of the clamping collar 84' and of the driving head sleeve 84 are both provided with a series of helically disposed flanges 92, which are of right hand pitch, and which are adapted to assist in mixing and "churning up" the mud charged water in the bottom of the bore hole; and also to aid in establishing and maintaining the upward movement of the liquid and the suspended solid material surrounding the exterior of the drill heads, and the drill stem. Similar flanges may be used, if desired, on the external peripheries of the drill head constructions previously described.

The operation of the rotary-reciprocating bit structure shown in Figs. 13 to 16 is substantially the same as that of the other constructions of this type previously considered, save that the reciprocating piston parts constitute in this case a "double acting" pump and serve to expel water from the orifices 44^a on both the up and the down strokes of the drill stem. These constantly flowing jets of liquid act on the turbine teeth or blades 90 to produce a constant semi positive revolution of the cutter disks 10^a in the same direction in which they tend to roll on the bottom of the hole as the drill rotates on its longitudinal axis. The drill head 6^a and the cutter members 10^a are held down to their work in the bottom of the hole, in part by the weight of the suspended members, in part by the excess pressure of the flushing liquid on the top of the drill head—due to the greater cross sectional area of the

upper piston chamber 41^a as compared with the lower piston chamber 88—in part by the action of the heavy compression spring 39^a; and in part by the reaction of the upwardly moving current of liquid on the flanges 92 of the rotating head 6^a.

The pump-turbo-reciprocating-rotary conversion device is not as certain and invariable in its action as the screw-gear conversion devices illustrated in Figs. 1, 8 and 11; but, under some conditions of operation, this flexibility of conversion action is an advantage. For this reason I have not illustrated any means for establishing a fixed ratio of movement between the reciprocable driving head 8^a and the revoluble cutter disks 10^a; nor have I provided in this last described illustrative embodiment of my invention any gear connections for synchronizing the rotary movements of the said disk members. But it is clear that the adjacent faces of the retaining flanges 95—on the inner ends of the cutter disk shafts 11^a—may be provided with teeth and geared together by a pinion in the manner illustrated in Fig. 1; and it is also clear that this pinion may be positively driven by a shaft screw and not connected like that shown in Fig. 8. Those skilled in this art will also appreciate that the first four constructions previously described may, on the other hand, be readily modified by omitting the screw-gear conversion devices—(or by temporarily rendering them inactive by the removal of one of the coating clutch or gear parts,) and relying solely on the pump-turbo conversion means for providing a revolution of the cutter disk independently of any movement due to the rotation of the drill head. Various other structural changes, both in the detail design and arrangement of the various parts, and in the manner of assembling the operative combination as a whole, will be readily suggested, to those familiar with these rotary drills, by the several typical embodiments which I have chosen to illustrate my present invention.

The characteristic features of operation of my improved type of reciprocating-rotary drill constructions—which are the common distinguishing characteristics of all of the varying forms of structure hereinbefore described—will now be clear without further explanation.

The effect of the combined reciprocatory and rotary movements of the drill stem or of the reciprocating movement alone will be to impart to the cutters a positive revolution on their axes which is independent of, or supplemental to, the usual rolling movement of these members on the bottom of the hole; this positive driving action being produced by, and due to the reciprocation of the drill stem. This positive drive will overcome any tendency of the cutters to clog and

- stick in the soft material at the bottom of the hole; and will further assist in a more even cutting away, and a more effective pulverization or disintegrated, of the material being drilled. The automatic alternate increase and decrease of pressure on the cutters of the drill—which results from the reciprocation of the drill stem—serves the purpose of preventing a too rapid penetration of soft materials and also permits the cutter members to periodically readjust themselves to the most effective operative position. Occasionally a rotary disk drill will, because of too great pressure, cut away the hole faster than the material thus loosened can be disintegrated and carried to the surface by the upward current of flushing water. This is very apt to result in a clogging or "balling up" of the bit. By the use of my improvement, however, the maximum pressure on the drill head can never exceed the maximum tension on the resilient members interposed between the driving head and the drill head on the downward stroke of the drill stem, and this can be easily and quickly controlled by simply varying the length of the reciprocating stroke, or by controlling the mean rate of descent of the reciprocating parts.
- 30 An additional means of preventing the clogging of the cutters of my improved type of bit is provided by the pumping action of the mutually reciprocable parts of the drill head and the driving head, which forces the water against the cutters, and the bottom of the hole, in a series of jets where velocity is quite independent of any difference in pressure between the supply of flushing liquid flowing downward through the hollow drill stem and the upwardly moving current of mud charged water surrounding the drill head. The reciprocating movement of the drill stem, and the members attached thereto, and the alternate increase and decrease of pressure on the bit head produced thereby, also serves to give the boring tool a continuous "spudding" and pumping action in churning up and carrying away the excavated material; and this further tends to prevent the "balling up" of the drill parts and the choking of the bore hole when operating in relatively soft strata.
- I thus obtain in my improved drill constructions a combination of advantages; which are only in part characteristic of the usual types of rotary bit structures—using cutters of either the cone roller or the inclined disk, or the vertical disk; or of the horizontal disk types—and are in part characteristic of the different forms of the reciprocating or "percussion" class of boring tools.
- Having thus described my invention what I claim as new and desire to protect by Letters Patent, is:
1. In a rotary well boring drill, the combination of a drill head, rotary cutters thereon, a hollow drill stem and a driving head interposed between the drill head and the drill stem and comprising two relatively reciprocable members, one of which is attached to the drill head, and the other of which is attached to the drill stem, said members acting when reciprocated to cause a positive rotation of said cutters.
  2. In a rotary well boring drill, the combination of a drill head, with a driving head having rotary cutters thereon secured thereto and comprising two telescopic members the upper one of which reciprocates relative to the lower whereby said rotary cutters are positively operated and means to transmit rotary movement from one of said members to the other.
  3. In a rotary well boring drill, the combination of a drill head, with rotatable cutters mounted thereon, and a driving head comprising two relatively reciprocable members one of which is secured to the drill head, and the other of which is adapted for attachment to a reciprocating drill stem, and means for preventing a relative rotary movement of the two members.
  4. In a rotary well boring drill, the combination of a drill head, rotatable cutters mounted thereon, a driving head secured to the drill head and comprising two relatively reciprocable members, and means for converting the reciprocating movement of one of these members into a positive rotary motion of the said cutters.
  5. In a rotary well boring drill, the combination of a drill head, rotatable cutters mounted thereon, a driving head secured to said drill head and comprising two relatively reciprocable members, a drive shaft mounted in the drill head, and geared to the rotatable cutters, and means acting on said shaft for converting the longitudinal movement of the reciprocating members into a rotary movement of the said drive shaft and the said cutters.
  6. In a rotary well boring drill, the combination of a drill head, rotatable cutters mounted thereon; a driving head secured to said drill head and comprising two relatively reciprocable members the upper one of which is adapted for attachment to a drill stem; means for transmitting rotary movement from one of said members to the other, and gearing connecting the reciprocating upper member to the rotatable cutters and adapted to convert the longitudinal movement of said member into a rotary movement of the said cutters.
  7. In a rotary well boring drill, the combination of a drill head; rotatable cutters

mounted thereon; a driving head secured to said drill head and comprising one member fixed to the drill head and another member longitudinally movable with respect to the head; a driving shaft longitudinally disposed in the reciprocating member; and means including said shaft for converting the longitudinal movement of the reciprocating member into a rotary motion of the 10 said cutters.

8. In a rotary well boring drill, the combination of a drill head; rotatable cutters mounted thereon; a driving head secured to said drill head, a driving shaft rotatably supported in said drill head and extending into said driving head; gears connecting said shaft and said cutters, and a reciprocating member mounted in said driving head and coöperating with said shaft to 15 rotate said cutters.

9. In a rotary well boring drill, the combination of a drill head; rotatable cutters mounted thereon; a rotatable driving head secured thereto; a shaft mounted in said 25 drill head and extending into the driving head, gears connecting the said shaft to the said cutters; and a screw connection between said driving head and said shaft whereby said shaft and cutters are rotated 30 independently of the rotation of said head.

10. A combination such as is set forth in claim 10, with separate means to rotate said drill head.

11. In a rotary well boring drill, the combination of a drill head, a rotatable cutter mounted thereon; means to rotate said drill head and separate means connected with said first mentioned means to produce an independent rotation of the said cutter, 35 comprising a rotatable shaft with operative connection to said cutter and a driving means for said shaft operated by the reciprocation of said drill head.

12. In a rotary well boring drill, the combination of a drill head; a rotatable cutter mounted thereon; a driving head comprising two relatively movable members; a sliding pin and slot engagement for transmitting rotary movement from one of said 45 members to the drill head; and separate means including a screw threaded shaft coöperating with a nut on the other of said members to impart an independent rotation to the rotatable cutter.

55 13. In a rotary well boring drill, the combination of a drill head a rotatable cutter mounted thereon; a driving head comprising one member secured to the drill head and a second member reciprocably mounted 60 on the first member; and means including a screw threaded shaft for producing a rotation of the said cutter by the reciprocation of said second member.

14. In a rotary well boring drill, the combination of a drill head, rotatable cutters

supported thereon, a driving head; a shaft mounted in the drill head; gears connecting the said shaft and the said cutters, and means actuated by the reciprocation of said driving head and coöperating with the said 70 shaft and the said driving head to rotate the shaft and the cutters, on their own axes.

15. A rotary well boring drill comprising in combination a drill head; rotatable cutters mounted thereon; a driving head secured to said drill head and comprising two relatively reciprocable members; a driving shaft mounted in the drill head and extending into the driving head; means for rotating the said shaft by the longitudinal movement of the reciprocable member and gears connecting the said shaft and the said 75 cutters.

16. In a rotary well boring drill, the combination of a drill head; a sleeve secured thereto; and a piston member reciprocably mounted in said sleeve, and constituting therewith a single action pump adapted to draw liquid from the space above the sleeve 90 and force it through chambers in the drill head to the lower end thereof.

17. In a rotary well boring drill, the combination of a drill head; rotatable cutters mounted thereon; a sleeve secured thereto and provided with water channels adapted to discharge flushing water on the rotatable cutters; and a piston member reciprocably mounted in said sleeve and provided with valve controlled channels 100 adapted to supply water to the piston chamber on the up stroke of said reciprocable piston member.

18. In a rotary well boring drill, the combination of a drill head; rotary cutters 105 mounted and housed therein, and means actuated by the movement of the drill parts for forcing streams of flushing fluid into the space surrounding the rotary cutters.

19. In a rotary well boring drill, the combination of a drill head; rotary cutters housed therein and means actuated by the movement of the drill parts for forcibly discharging jets of flushing water against the 110 said cutters.

20. In a rotary well boring drill, the combination of a drill head; rotatable cutters housed therein; and a driving head comprising a sleeve, a piston member reciprocable in said sleeve, and means for utilizing 120 the reciprocation of the piston member for forcibly discharging jets of water on the said cutters.

21. In a rotary well boring drill, the combination of a drill head; rotatable cutters 125 housed therein; a driving head comprising one member fixed to the drill head and a second member reciprocably mounted thereon, means for converting the reciprocating movement of the second member into a ro- 130

tary movement of the cutters on said head and means to hold the cutters in continuous cutting engagement with the bottom of the hole.

- 5 22. In a rotary well boring drill, the combination of a drill head; rotatable cutters mounted thereon; a collar attached to said drill head; a reciprocable member adapted for attachment to a drill stem; gearing connecting the said reciprocable member with the cutters and adapted to positively rotate said cutters by the reciprocating movement of said member; and means to prevent reciprocation of the drill head.
- 10 23. In a rotary well boring drill the combination of a head, a cutter revolvably supported thereon, a member reciprocably mounted on the said head, and means for revolving the said cutter by the reciprocable movement of the said member.

15 24. In a rotary well boring drill the combination of a head, a revoluble cutter carried by the said head, a reciprocable member mounted on the head, and means for revolving the said cutter by the relative reciprocable movement of the member and the head.

20 25. In a well boring tool the combination of a rotary head, a reciprocable member and a revoluble cutter mounted thereon and reciprocable rotary conversion means adapted to produce a rotary movement of the cutter on said head by the reciprocable movement of the member on the head.

25 26. In a rotary well boring drill the combination of a drill head, a rotatable cutter

supported thereon, a reciprocable member mounted on an extension of said drill, means for utilizing the reciprocating movement of said member to rotate the rotatable cutter 40 on its axis, and other means for utilizing said reciprocating movement to forcibly discharge jets of water into the space adjacent said rotatable cutter.

27. In a rotary well boring drill the combination of a drill head, a cutter rotatably mounted thereon, a driving head secured to said head and comprising a reciprocable member; means for utilizing the reciprocation of the said member to force jets of 50 water into the space around the rotatable cutter; and other means for converting the reciprocating movement of said member into a rotary driving movement of the said cutter.

55

28. In a rotary well boring drill the combination of a drill head, a cutter revolvably supported thereon, a sleeve member secured to said head, a piston member shaped for attachment to a hollow drill stem and reciprocably mounted in the sleeve member, means for utilizing the reciprocating movement of the piston member to draw water from the interior of the hollow drill stem and force it through openings in the drill 65 head; and other means for converting the said reciprocating movement into a revolving movement of the revoluble cutter.

60

In testimony whereof I hereunto affix my signature this the 28th day of January, A. 70 D. 1919.

FRANK L. O. WADSWORTH.
